LIGHT FIXTURE

Peter Simon, 1255 W. Chippewa River Road,
Midland, Mich.

Original design application Apr. 4, 1963, Ser. No. 74,303.
Divided and this application June 22, 1964, Ser. No.
80,771

Term of patent 14 years

(Cl. D48—31)

FIGURE 1 is a side elevational view of a light fixture embodying my new design;

FIGURE 2 is an end elevational view thereof;

FIGURE 3 is a top plan view thereof;

FIGURE 4 is a partly sectional and partly bottom plan view thereof, the section being taken on the line 4-4 of FIGURE 1;

FIGURE 5 is a side elevational view of the modified light fixture embodying my new design;

FIGURE 6 is an end elevational view thereof;

FIGURE 7 is a top plan view thereof;

FIGURE 8 is a partly sectional and partly bottom plan view thereof, the section being taken on the line 8-8 of FIGURE 5.

The fragmentary showing of the post in the drawings is for illustrative purposes only.

This application is a division of application Serial No. D. 74,303, filed April 4, 1963.

I claim:

The ornamental design for a light fixture, as shown and described.
